Primary Examiner — Holly E Thurman*(74) Attorney, Agent, or Firm* — Boyle Fredrickson, S.C.(57) **CLAIM**

The ornamental design for a baby carrier, as shown and described.

DESCRIPTION

1. Baby carrier
1.1 is a perspective view of a baby carrier in accordance with the present invention;
1.2 is a front elevational view of the baby carrier of Fig. 1.1;
1.3 is a rear elevational view of the baby carrier of Fig. 1.1;
1.4 is a side elevational view of a first side of the baby carrier of Fig. 1.1;
1.5 is a side elevational view of a second side of the baby carrier of Fig. 1.1;
1.6 is a top plan view of the baby carrier of Fig. 1.1; and
1.7 is a bottom plan view of the baby carrier of Fig. 1.1. The broken lines in the drawings depict portions of the baby carrier that form no part of the claimed design.
